UNITED STATES PATENT OFFICE.

FREDERICK J. KALDENBERG, OF NEW YORK, N. Y.

DESIGN FOR AN UMBRELLA-HANDLE.

SPECIFICATION forming part of Design No. 11,731, dated April 13, 1880.

Application filed February 26, 1880. Term of patent 3½ years.

To all whom it may concern:

Be it known that I, FREDERICK J. KALDENBERG, a citizen of the United States, residing at New York, in the county and State of New York, have invented and produced a new and original Design for Umbrella or Parasol Handles, of which the following is a specification, reference being had to the accompanying drawing, forming part thereof.

10 The object of my invention is to produce an attractive and peculiar configuration for the handles of umbrellas or equivalent articles; and it consists chiefly in forming upon the handle the representation of the ancient harp.

15 The accompanying drawing clearly illustrates, in a side view, a parasol-handle of my design.

20 *a* is the body of the handle, which is round in general contour. *b c d* is an ornate figure resembling the ancient harp. The strings, which may be of gilded or silvered wire, and either plain or embossed, are shown as extending diagonally across to represent a peculiar form of harp; but this is a matter of preference only.

25 The general outline of the harp is triangular; but I may prefer to slightly vary its form, in order that its proportions and outline shall harmonize with the embellishments employed upon the handle.

30 *e* represents the face and head of a child

encircled by floral and leaf-like ornamentations *ff*. The ornamentation *g* at the base of the harp is designed to represent reflected leaves and curved or bent foliage. The peculiar ornamentation surrounding the face of the child may consist of intertwining vines and leaves, or of fruits and flowers intermixed, as preferred, without affecting the special character of my design.

35 40 What I claim as my invention, and desire to secure by Letters Patent, is—

1. The design for the handle of an umbrella or parasol, consisting of the representation of a harp on the top of the handle, substantially 45 as described, and as shown in the accompanying drawing.

2. The design for an umbrella or parasol handle, consisting of the representation of a harp, with the head of a child encircled with 50 leaf-like or other foliate ornamentation upon it, substantially as described, and shown in the accompanying drawing.

3. The design for an umbrella or parasol handle, consisting of the representation of a 55 harp placed on the top of the handle, with floral ornamentation beneath it, as described, and shown in the accompanying drawing.

FREDERICK J. KALDENBERG.
